SURFACE ORNAMENTATION OF WALLS.

No. 18,689.

Patented Oct. 16, 1888.

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,689, dated October 16, 1888.

Application filed September 24, 1888. Serial No. 286,299. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification, reference being had to the accompanying photograph, forming part hereof.

My design consists in a series of rectangular elevations, A, and flat surfaces and inclined sides. Said elevations are arranged diagonally across the surface to be ornamented. Between said elevations are groups, B, of two parallel raised bars having rounded surfaces.

Between the diagonal rows of elevations are groups of two parallel raised bars, C, alternating with groups of four rectangular elevations, D. The bars C are parallel to the edges of the elevations A.

I claim—

The design for the surface ornamentation of walls, &c., substantially as herein shown and described.

FREDERICK KOSKUL.
